UNITED STATES PATENT OFFICE.

IRA H. SHATTUCK, OF HOLLYWOOD, CALIFORNIA.

TOWEL-CABINET.

1,092,405.

Specification of Letters Patent. Patented Apr. 7, 1914.

Application filed October 25, 1911. Serial No. 656,786.

To all whom it may concern:

Be it known that I, IRA H. SHATTUCK, a citizen of the United States, residing at Hollywood, in the county of Los Angeles and 5 State of California, have invented a new and useful Towel-Cabinet, of which the following is a specification.

My invention relates to a towel cabinet, being particularly designed for use in hotels, 10 depots and similar places where it is not expedient to supply each individual with a separate towel, and one of the main objects of my invention is to produce a towel cabinet adapted to contain a long strip of toweling and to expose successively different portions of the toweling in such a manner that 15 each individual using the towel may operate the cabinet to expose a clean portion of towel for his own use.

Another object of my invention is to produce a towel cabinet of the character described of simple and economical construction which may be operated with great simplicity.

Other objects and advantages will appear hereinafter from the following specification.

Referring to the drawings, which are for illustrative purposes only:—Figure 1 is a perspective view of a cabinet embodying my 30 invention, showing the manner in which a portion of the towel is exposed for use. Fig. 2 is a vertical sectional view taken through the cabinet. Fig. 3 is a vertical sectional view on line x^3-x^3 Fig. 2. Fig. 4 is an enlarged side view of the feed roll supporting device. Fig. 5 is a face view of the towel spool or drum. Fig. 6 is a sectional view on line x^6-x^6 Fig. 5. Fig. 7 is a vertical sectional view of a cabinet showing a modified 40 form of my invention. Fig. 8 is an enlarged view of a portion of the device shown in Fig. 7.

The cabinet comprises a box or case 1 having a top and bottom 2 and 3, respectively, 45 and side walls 4 and 5. The front of the cabinet 1 is provided with a door 6 having a mirror 7 in the upper part thereof, the door 6 being hinged at 8 to the wall 4 of the cabinet and held in closed position by any suitable fastening means, such as a lock 9. Upon the rear of the door 6 is mounted a pair of brackets 10 extending inwardly therefrom, each bracket 10 being provided with a recess 11 to receive the ends of a rod 50 or shaft 12 of a spool or drum 13. On the inner side of each bracket 10, slidably mount-

ed on the shaft 12, is a washer 14 against the inner face of which abuts the outer end of a coil spring 15. The inner end of each coil spring 15 abuts against the adjacent 60 end 13' of the drum and thereby holds the drum 13 in central position between the brackets.

The spool 13 above described comprises a charging roller for the towel cabinet. A 65 long strip of toweling 16 is secured to the roller by inserting one end of the strip in a groove 17 formed in a hub 17' mounted on shaft 12. The end of the toweling is pressed tightly in the groove 17 by means of a bar 18 mounted on springs 19, which springs 19 are secured to the hub 17' by means of screws 20, or in any other suitable manner. The ends of the bar 18 extend through slots 21 formed in the end 13' of the spool, so that 70 the ends of the bar 18 may be easily grasped by the person securing the towel on the spool. The toweling is then wound tightly around the hub of the spool and the free end of the toweling passed downwardly from the 75 spool between an upper roller 22 and an intermediate roller 23, thence through a slot 24 formed in the door 6 of the cabinet, thence extending downwardly outside of the cabinet forming a loop 25, thence through a slot 80 26 below the slot 24 in the door of the cabinet, thence between the intermediate roller 23 and a lower roller 27. The end 28 of the toweling extends downwardly into the interior of the cabinet wherein it piles up in the manner indicated at 29 on the bottom 3 of the cabinet. The rollers 22, 23 and 27 are provided with shafts 30, 31 and 32, respectively, which extend outwardly from the ends of the respective rollers. The ends of the shaft 90 30 are supported in blocks 33 mounted to slide vertically in slots 34 formed in a frame 35. The ends of the shaft 31 of the intermediate roller 23 are mounted in slots 36 which are formed in the frame 35, and the 100 shaft 32 of the roller 27 is rotatably mounted in the frame 35. The rollers are held in frictional contact with the strip of toweling 16 by means of springs 37 interposed between vertically slidable blocks 37' on the end of screws 38 and the top of the blocks 33. The screws 38 are mounted in suitable brackets 39 secured to the frame 35 and are also provided at their upper ends with handle means 40. On the outer side of each frame pivotally mounted on a pin 41 is an arm 42 having a curved upper portion 43 and a straight

handle portion 44 extending downwardly therefrom. The curved portion 43 of each arm 42 is in contact with the under face of the adjacent block 33, which block 33 presses the arm 42 downwardly so that the inner face of the arm bears against the shaft 31 of the roller 23, thereby holding the shaft 23 of the roller in the slot 36 of the frame 35. This construction provides a means for quickly removing the roller 23 for the purpose of threading the strip of toweling between the rollers and through the slots in the door of the cabinet which is accomplished by swinging the arms 42 upwardly and outwardly which raises the roller 32 and clears the slots 36 so that the intermediate roller 23 may be readily removed from the frame 35.

The rollers 22, 23 and 27 are preferably formed with a coating of rubber which provides a frictional contact between the rollers and strip of toweling therebetween, thereby preventing the toweling from being twisted between the rollers. The rollers 22, 23 and 27 are driven through gear 50 mounted on the end of shaft 30 of the upper roller, gear 51 mounted on the shaft 31 of the intermediate roller, and gear 52 mounted on shaft 32 of the lower roller, which gears 50, 51 and 52 are in mesh with each other. The shaft 32 of the lower roller 27 is also provided with a gear 53 meshing with an intermediate gear 53' on the side wall 5 which meshes with a driving gear 54 mounted on a shaft 55 which extends through the side wall 5 of the cabinet to the exterior thereof, at which point the shaft 55 has mounted thereon crank means 56.

The loop 25 of the strip of toweling 16 which extends through the slots 24 and 26 formed in the door 6 of the cabinet is of sufficient length to provide an ample length of toweling for a person to freely use the same.

The cabinet above described is operated in the following manner. The spool 13 containing a long strip of clean toweling having been mounted in the brackets 10, as above described, the end of the strip of toweling is then passed between the upper and intermediate rollers 22 and 23, respectively, thence through the slot 24 in the door of the cabinet to the exterior thereof, thence returning to the exterior of the cabinet through slot 26 in the door, forming a loop 25 in front of the cabinet, as above described, thence between the intermediate and lower rollers 23 and 27, respectively, and is ready for use. After a portion of the loop 25 has been used and become soiled, the next person desiring to use the towel operates the crank 56 on the shaft 55 and drives the rollers 22, 23 and 27 respectively, through gears 54, 53, 52, 51 and 50. The

action of the rollers pulls the strip of toweling 16 therebetween causing the spool 13 to rotate, unwinding the strip of toweling therefrom which passes through the slot 24 to the outer side of the loop 25, the soiled portion of the toweling passing to the rear of the loop 25, or to the unexposed portion thereof, thereby presenting a clean strip of toweling on the front of the loop 25. The return portion of the loop 25 passes through the slot 26 in the door 6, thence between rollers 23 and 27 to the bottom of the cabinet where it piles up until the clean toweling on the spool 13 has been exhausted. The end of the toweling is then removed from the spool 13 and the soiled toweling removed from the bottom of the cabinet and either an entirely new spool with clean toweling thereon is placed in the brackets 10, or a clean strip of toweling is mounted on the spool 13 while the same is still in the cabinet. In either case the outer end of the clean strip of toweling is mounted in the rollers and slots in the front of the cabinet, as heretofore described.

For the purpose of preventing a strip of toweling from becoming loose between the spool 13 and the rollers 22 and 23, a friction device is mounted on one of the brackets 10, consisting of a flat spring 57 provided with a shoe 58 which is pressed against one of the ends 13' of the spool by means of bolt 59 mounted in a bracket 60, which bracket 60 is secured in any suitable manner to one of the brackets 10.

In the form shown in Figs. 7 and 8, the cabinet is designed to be operated by a suitable source of electrical energy, in which case the gear 53 on the shaft 32 meshes with a gear 60 driven by a gear 61 which in turn is driven by a train of gears 62 from a motor 63. The gear 61 is mounted on a shaft 61' secured to the side wall 5 of the cabinet and is provided with a circular depression or recess 83 on one face thereof. At one portion of the recess 83, in the face of the gear 61, is provided a perforation 64 which extends through the gear 61 and having inserted therein a sleeve 65 of insulating material. A bracket 66 is mounted on the side wall 5 of the cabinet in any suitable manner and insulated therefrom by means of an insulating block 67. Pivoted mounted at 68 on the bracket 66 is an arm 69 having a rounded head 70 on the upper end thereof, which head 70 is adapted to ride in the recess 83 formed in the face of the gear wheel 61 and also adapted to enter the opening in the sleeve 65 when the gear wheel is in proper rotative position to be engaged thereby. The upper end of the arm 69 is also provided with an extension 71 adapted to contact with a plate 72. Pivoted to the lower end of the arm 69, and extending through an opening 73 in the side wall 5 of

the cabinet, is a rod 69', the outer end of which is adapted to be pressed by the finger of the person operating the cabinet. The head 70 of the arm 69 is held in engagement with the recess 83 in the face of the gear 61 or with the opening in the insulating sleeve 65, as the case may be, by means of a spring 74 interposed between the arm 69 and the side wall 5 of the cabinet. The motor is connected by wire 75 to the arm 69 and by wire 76 to the shaft 61' of the gear wheel 61. The motor is also connected through wire 76 and wire 77 to plate 72 on the inner side of the side wall 5 of the cabinet.

15 The form of cabinet shown in Figs. 7 and 8 is operated in the following manner. It is understood that the form shown in Figs. 7 and 8 is provided with a spool 13 and with rollers 22, 23 and 27 of the same form as that shown in the preceding figures, and that the strip of toweling is threaded through the rollers and through the slots in the door of the cabinet in the same manner as heretofore described in reference to the preceding figures. When it is desired to operate the cabinet for the purpose of exposing a clean strip of toweling, the rod 69' is pressed inwardly which raises the head 70 free of the sleeve 65 in the gear wheel 61, which same action brings the extension 71 into contact with plate 72. This position of the arm 69 closes an electric circuit from the plate 72, wire 77 and wire 76 to the motor, and from the motor through wire 75 to the arm 69, which starts the operation of the motor, thereby driving the rollers 22, 23 and 27 through gears 50, 51, 52, 53, 60, 61 and train of gears 62, during which operation gear wheel 61 rotates in the direction of the arrow shown in Fig. 7. Upon the pressure on rod 69' being released, the spring 74 moves the extension 71 on the upper end of the arm 69 away from plate 2, thereby breaking the circuit through the wires just described and bringing the head 70 on the arm 69 into engagement with the recess 83 of the gear wheel 61, thereby closing a circuit through gear wheel 61, shaft 61', wire 76, motor 63, wire 75 and arm 69, thereby causing the continued operation of the motor until the gear wheel 61 has made a single rotation and the insulating sleeve 65 has moved under the head 70 on the arm 69, at which point the spring 74 presses the head 70 into the opening in the sleeve 65, which sleeve 65 breaks the circuit between gear wheel 61 and the arm 69, and at the same time the engagement of the head 70 with the sleeve 65 prevents further rotation of the gear wheel 61.

10 It is understood that the diameter of the gear wheel 61 is designed so that a single rotation of the gear wheel permits the required movement of the strip of toweling to present a clean portion of the same for use.

15 What I claim is:—

A towel cabinet comprising a case having an upper and lower slot therein, a pair of frames secured to the inside of said case, each having a vertical slot therein and a horizontal slot therein, a lower roller rotatably mounted on said frames, a shaft mounted in said horizontal slots, an intermediate roller mounted on said shaft, a block in said vertical slot slidable therein, a shaft mounted in said blocks, an upper roller mounted on said last named shaft, a curved arm mounted on each frame engaged by one of said blocks and extending between the shaft on the intermediate roller and the upper end of the horizontal slots in said frames, a spool mounted in said case and adapted to receive a strip of toweling thereon, and so placed as to admit of passing one end of the strip of toweling between said upper and intermediate roller in said case, thence through said upper slot to the exterior of the case to form a loop, thence through the lower slot in said case, thence between the intermediate and lower rollers in said case, and means for rotating said rollers to cause said strip of toweling to travel therebetween.

20 In testimony whereof, I have hereunto set my hand at Los Angeles, California, this 20th day of October, 1911.
